(57) **CLAIM**

The ornamental design for an extraction tool as shown and described.

DESCRIPTION

FIG. 1 is a front and top perspective view of an embodiment of an extraction tool showing our new design;

FIG. 2 is a front side view thereof;

FIG. 3 is a rear side view thereof;

FIG. 4 is left side view thereof;

FIG. 5 is a right side view thereof;

FIG. 6 is a top view thereof; and,

FIG. 7 is a bottom view thereof.

The broken lines depict environmental structure that forms no part of the claimed design.
